CLYDE E. BROWN, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

WEFT DETECTING MECHANISM FOR DOUBLE SHUTTLE LOOMS

Application filed May 13, 1931. Serial No. 537,090.

This invention relates to automatic weft replenishing looms using two shuttles and having shifting shuttle boxes at the weft detecting side of the loom.

5 It is the general object of my invention to provide an improved construction by which the weft detectors will indicate the condition of the weft supply in a shuttle about to become active but will give no indication for 10 a shuttle about to become inactive.

A further object is to provide a construction by which the weft detectors will continue to indicate a shuttle which remains for several picks in active or running position 15 but will cease such indication when said shuttle is about to become inactive.

My invention further relates to arrangements and combinations of parts which will be hereinafter described and more particularly pointed out in the appended claims.

A preferred form of the invention is shown in the drawing, in which

Fig. 1 is a side elevation of parts of a loom embodying my improvements, with the lay 25 and shuttles shown in section;

Fig. 2 is a sectional plan view of the weft detecting mechanism, taken along the line 2—2 in Fig. 1,

Figs. 3 and 4 are diagrammatic views, 30 illustrating the operation of my invention, and

Fig. 5 is a detail sectional view, taken along the line 5—5 in Fig. 2.

Referring to the drawing, I have shown 35 a portion of a loom frame 10 having a bracket 11 secured thereto. The bracket 11 is provided with upwardly extending guideways 12 for a bar 13, slidably mounted therein. Arms 15 and 16 project laterally from 40 the slide bar 13 and constitute supports for upper and lower weft detecting devices W and W'. The slide bar 13 is also provided with a stud or projection 20 for a purpose to be described.

45 The usual lay 22 is provided with drop boxes 23 mounted on the usual lifter rod 24 and positioned by the usual box mechanism, controlled by a pattern chain or in any other convenient manner. Upper and lower 50 shuttles S and S' are received in the upper

and lower drop boxes respectively. The upper weft detecting device W has a detecting member D adapted to contact with the bobbin B in the upper shuttle S and the lower detecting device W' has a detecting member D' adapted to contact with the bobbin B' in the lower shuttle S'. 55

A bracket 30 is secured to the lower side of the drop boxes 23 and is provided with a segmental slot 31 at its forward end, within 60 which the stud 20 is received as the lay 22 and the drop boxes 23 move forward. After the stud 20 enters the slot 31, the detecting devices partake of the upward or downward movement of the boxes. 65

An elongated transmitting member 40 (Fig. 1) is pivoted at 41 on the bracket 11 and is provided with an arm 42 adapted to be swung into the path of a chopper lever 43 constituting a part of the actuating connections of the usual weft replenishing mechanism. 70

When the arm 42 is swung into the path of the lever 43, weft replenishment will be initiated but when the arm 42 is out of the path of movement of the lever 43, the lever 43 will remain inoperative. These connections are of the usual type and in themselves constitute no part of my present invention. 75

The detecting devices W and W' are identical in construction and the details of construction of the upper detecting device W are shown in Fig. 2. The detecting member D is pivoted at 50 on a slide 51, formed in two parts and having a lug or projection 52 at its forward end. A single spring 53 moves the detecting device D and slide 51 rearward and also holds the detecting device D against a stop pin 54. 80

When engaged by a substantial supply of weft on a bobbin B, the detector D moves forward in a straight line without angular movement and slides past the transmitting device 40 without imparting angular movement thereto. If, however, the weft is substantially exhausted on the bobbin engaged by the detector D, the detector swings on its pivot 50 in the direction of the arrow α in Fig. 2, causing corresponding movement of the transmitting device 40 and arm 42 and 90 95 100

thus rendering the weft replenishing mechanism active. The lower detecting device D' is provided with a projection 52', corresponding to the lug 52 of the detecting device D.

5 It is desirable that the condition of the weft be indicated only in a shuttle about to become active or about to remain active, and not in a shuttle about to become inactive.

For this purpose I provide upper and 10 lower shields 60 and 61, pivoted at 62 and 63 on the side of the front guideways 12. These shields are provided with side flanges 64 and 65 and additional fixed lugs or projections 66 and 67 are associated therewith. The 15 flanges 64 and 65 have cam-shaped portions inclined inwardly, which operate as will be hereinafter described. These flanges 64 and 65 are cut away or shortened at each end thereof and the shield members are held 20 yieldingly in the positions shown in Fig. 1 by springs 68.

A spring plunger 70 is mounted in the stand or support 11 and is adapted to engage upper and lower notches 71 and 72 in the back 25 side of the slide bar 13. The plunger 70 yieldingly prevents upward or downward displacement of the slide bar 13 when the stud 20 is out of the open slot 31.

Having described the details of construction of my improved weft detector mechanism, the method of operation thereof is as follows:

Assuming the boxes to be raised, the lugs 35 52 and 52' on the front-ends of the detector slides 51 and 51' will occupy the positions indicated in Fig. 3. So long as the boxes remain in this position, the upper detector D will be held forward out of operative position by engagement of the lug 52 with the 40 upper fixed projection 66, while the lower projection 52' will be positioned between the adjacent ends of the upper and lower shields 60 and 61. Consequently the upper detector will be held inoperative, while the lower detector will be free to operate.

When the boxes are lowered, however, the engagement of the bracket 30 with the stud 20 will cause the detecting devices to be correspondingly moved downward. As the detecting devices move downward, the lug 52' 50 of the lower detecting device D' will engage the flange 65 of the lower shield 61 and will be moved forward to inoperative position, as shown by the arrows in the lower part of Fig. 3.

As the boxes reach their extreme lowered position, the lug 52' will slip off of the lower end of the flange 65 but will be caught by the lower fixed projection 67, as shown at the 60 bottom of Fig. 4, and will thus be held inoperative so long as the boxes remain in lowered position.

During the same downward movement of the boxes, the projection 52 of the upper detector slide 51 will slip downward and off of

the fixed projection 66 and will thereafter move downward behind the shield 60, as indicated by the arrows in the upper part of Fig.

3. The upper detecting device D will thus be operative to detect the condition of the 70 weft supply in the upper shuttle S, as the upper shuttle moves downward to active position.

When the boxes reach their extreme lowered position, the lug 52 occupies the mid-position indicated in Fig. 4 and will continue to indicate the upper shuttle S until the boxes are again moved upward, when the lower detecting device D' will become operative and the lug 52 will follow the path 80 of the arrows indicated in the upper part of Fig. 4, holding the upper detecting device D inoperative.

I have thus provided very simple mechanism for holding a detector inoperative so long as the corresponding shuttle remains inoperative and until the shuttle is about to become active, and I have also provided mechanism by which the detecting device associated with a shuttle in running position will 90 remain operative until said shuttle is about to become inactive. Furthermore, this extremely desirable result is attained by a very simple addition to the usual weft detector mechanism.

The object of forming the detector slide 51 in two parts is to provide lost motion, so that the projections 52 and 52' will not be forced against the under sides of the flanges 64 or 100 65 during a detecting movement, thus unnecessarily increasing the pressure on the detector and weft.

Having thus described my invention and the advantages thereof, I do not wish to be limited to the details herein disclosed, otherwise than as set forth in the claims, but what I claim is:—

1. In a loom having a pair of shuttle boxes, means to shift said boxes and a weft detecting device associated with each shuttle box, 110 in combination, a separate shield for each detecting device effective to render its associated device inoperative when the associated shuttle is becoming inactive, and an additional device effective to hold said detecting device inoperative until the associated shuttle 115 is about to become again active.

2. In a loom having a pair of shuttle boxes, means to shift said boxes and a weft detecting device associated with each shuttle box, 120 in combination, a separate shield for each detecting device effective to render its associated device inoperative as the associated shuttle is moving to inactive position, and an additional device effective to hold said detecting device inoperative until the associated shuttle begins a return movement to active position.

3. In a loom having a pair of shuttle boxes, means to shift said boxes and a weft detect- 130

ing device associated with each shuttle box, in combination, a separate shield for each detecting device effective to render its associated device inoperative as the associated shuttle is removed vertically from running position, and an additional device effective to hold said detecting device inoperative until the associated shuttle begins to move vertically back to running position.

4. The combination in a loom as set forth in claim 2, in which each weft detecting device has a lateral projection and in which each associated shield has a cam-shaped flange positioned for engagement by said lateral projection when the associated shuttle is moving to inactive position, said flange being shorter at each end than the limits of travel of said lateral projection, and in which a fixed abutment is provided for engagement by said lateral projection when in its extreme inactive position.

5. In a loom having a pair of shuttle boxes, means to shift said boxes and a weft detecting device associated with each shuttle box, in combination, means to move forward to inoperative position the weft detecting device associated with the shuttle becoming inactive and to thereafter release said device, and additional means to thereupon engage and hold said released detecting device inoperative until return movement of said shuttle to active position has begun.

6. In a loom having a pair of shuttle boxes, means to shift said boxes and a weft detecting device associated with each shuttle box, in combination, a shield associated with each detecting device, said shield having a cam-shaped flange and said detecting device having a portion moving behind said flange from inactive to active position of the associated shuttle and moving in front of said flange and in engagement therewith as the associated shuttle moves from active to inactive position, and separate means to hold said detecting device inactive when said shuttle is in extreme inactive position and until the return movement of said shuttle to active position begins.

7. The combination in a loom as set forth in claim 6, in which each separate means is positioned slightly rearward of its associated flange, whereby said detecting device is disengaged from said flange but is maintained inoperative by said separate means after such engagement and while in extreme inactive position.

In testimony whereof I have hereunto affixed my signature.

CLYDE E. BROWN.
